UNITED STATES PATENT OFFICE

161,057

LADY'S DUNGAREES

Minnie M. Schwab, Birmingham, Ala., assignor
to Phillips-Lester Manufacturing Company,
Inc., a corporation of Alabama

Application February 6, 1950, Serial No. 7,754

Term of patent 14 years

(Cl. D3—17)

To all whom it may concern:

Be it known that I, Minnie M. Schwab, a citizen of the United States, residing at Birmingham, State of Alabama, have invented a new, original, and ornamental Design for Lady's Dungarees, of which the following is a specification, reference being had to the accompanying drawing, forming a part hereof.

Fig. 1 is a front elevational view of lady's dungarees, showing my new design;

Fig. 2 is a rear elevational view thereof;

Fig. 3 is an enlarged fragmental plan view thereof illustrating the appearance of the upper edge of the garment and the fastening means therefor; and,

Fig. 4 is an enlarged fragmental front elevational view thereof.

I claim:

The ornamental design for lady's dungarees, as shown.

MINNIE M. SCHWAB.
